UNITED STATES PATENT OFFICE.

ELMER KING, OF ANN ARBOR, MICHIGAN.

CARRIER OR STRETCHER.

Application filed October 25, 1921. Serial No. 510,209.

To all whom it may concern:

Be it known that I, ELMER KING, a citizen of the United States, residing at Ann Arbor, in the county of Washtenaw and State of Michigan, have invented certain new and useful Improvements in Carriers or Stretchers, of which the following is a specification.

This invention relates to a stretcher or sling for moving helpless or other persons.

10 The object of the invention is to provide a carrier so constructed that one can carry with ease a person of the heavy weight without any strain upon the person carried.

Another object is to provide a device of 15 this character which shall be adjustable and distribute the weight of the person carried so as to equalize the strain on the person from whom the device is supported.

With these and other objects in view, the 20 invention consists in certain novel features of construction as hereinafter shown, described and claimed.

In the accompanying drawings:—

Figure 1 represents a front elevation 25 showing this improved stretcher in use.

Fig. 2 is a perspective view showing the device in the act of being applied.

Fig. 3 is a plan view of the stretcher in open position.

30 Fig. 4 is a detail longitudinal section taken on the line 4—4 of Fig. 3; and

Fig. 5 is a similar view taken on the line 5—5 of Fig. 3.

In the embodiment illustrated the stretcher 35 or carrier including a body portion 1, formed from a length of heavy duck or canvas with the opposed ends thereof reinforced by the folding and hemming down thereof as shown at 2, and to which are secured the fastening devices as will now be 40 described.

A strong leather suspension strap 3, is secured at one end to one end of the body portion 1, adjacent one side edge thereof 45 preferably by riveting, and is detachably secured at its other end to the opposed side edge of the body portion by a buckle 4.

Two rings 5 and 6 are loosely connected with that end of the body portion 1, which 50 carries the strap 3, being preferably secured by keepers 7, which are riveted to the body portion as is shown clearly in Fig. 4.

The strap 3 and buckle 4 are connected with the body portion 1, by a U-shaped clip 55 8, riveted or otherwise secured to the body portion 1. One of the clips 8 extends

through the buckle 4, for connecting it to the body portion, but the other clip 8 is provided with a metal loop 9, to which the strap 3 is secured. 60

Secured to the other end of the body portion 1, adjacent the opposed side edges thereof, are two snap hooks 10 and 11, said hooks being shown secured by U-shaped clips 12, similar to those employed in connecting the strap carrying buckle. 65

The canvas body from which the stretcher or carrier is constructed, is of a width sufficient to extend far enough down on the lower extremities to hold them up and far enough up on the shoulders so that the head 70 will rest comfortably without strain on the patient. This body portion 1 is of a length sufficient to encompass the body of the person to be carried forming a swinglike contrivance when in use as is shown clearly in Figs. 1 and 2. 75

In the use of this device the strap 3, is first connected with the buckle 4 and then the body portion 1, is passed transversely 80 under the body of the person to be lifted, and the snap hooks 10 and 11, engaged with the rings 5 and 6, as shown clearly in Fig. 2. The strap 3, is then passed over the head of the one who is to lift the person in the 85 stretcher and such strap passed over one shoulder and under the other arm, as is clearly illustrated in Fig. 1. This arrangement of the strap distributes the weight of the person in the stretcher so that a very 90 heavy weight may be carried by one who is comparatively light. This stretcher is especially useful for firemen in carrying out people who have been overcome with smoke, etc., or any other person in a helpless condition. 95

As shown clearly in Fig. 1 when the body portion 1 is placed around the person to be lifted and the strap engaged over the shoulders of the lifting person, the hands of the latter will be free so that he may put one under the head of the person lifted and the other under the knees as shown and thereby prevent the head of an unconscious person dropping down or any strain being exerted 105 thereon.

From the above description it will be obvious that this device is simple, inexpensive and exceedingly convenient for carrying helpless persons without fatigue and at the 110 same time leave the hands free to attend to other duties. This device has the further

advantage that it may be folded up into small compass to be stored in small space when not required for use.

The preferred embodiment of the invention is disclosed in the drawings and set forth in the specification, but it will be understood that any modifications within the scope of the claimed invention may be made in the construction without departing from the principle of the invention or sacrificing any of its advantages.

I claim:—

1. A carrier for the purpose set forth comprising a rectangular flexible body portion, a suspension strap, a yoke-shaped member projecting from one end of the body portion and connecting said strap thereto, a buckle adapted to have said strap connected thereto, a yoke-shaped member projecting from the said end of the body portion and connecting said buckle thereto, a ring connected to each of said members intermediate the ends thereof, a pair of yoke-shaped elements connected to the other end of the body portion and projecting therefrom, and hook elements carried by said

yoke-shaped elements and adapted to detachably engage said rings whereby the ends of the body portion are connected together.

2. A carrier for the purpose set forth comprising a rectangular flexible body portion, a suspension strap, a yoke-shaped member secured to and projecting from one end of the body portion and connecting said strap therewith, a buckle adapted to have said strap connected thereto, a yoke-shaped member secured to the said end of the body portion and connecting said buckle therewith, a ring positioned on each of said members intermediate the ends thereof, means for loosely connecting said rings to said members, a pair of yoke-shaped elements secured to and projecting from the other end of the body portion, and hook elements carried by said yoke-shaped elements and adapted to be detachably connected to said rings whereby the ends of the body portion are connected together.

In testimony whereof, I affix my signature hereto.

ELMER KING.
